GOLF PUTTER HEAD

Raymon W. Cook, 406 Top Hill,
San Antonio, Tex. 78209

Filed Mar. 21, 1973, Ser. No. 343,517

Term of patent 14 years

Int. Cl. D21—02

U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a vertical sectional view, taken on the line 5-5 of FIG. 4, looking in the direction of the arrows.

FIG. 6 is a bottom plan view of FIG. 1.

FIG. 7 is a front elevational view of another embodiment of my invention.

FIG. 8 is a front end view of FIG. 7.

FIG. 9 is a top plan view of FIG. 7.

FIG. 10 is a rear elevational view of FIG. 7.

FIG. 11 is a vertical sectional view, taken on the line 11-11 of FIG. 10, looking in the direction of the arrows.

FIG. 12 is a bottom plan view of FIG. 7.

I claim:

The ornamental design for a golf putter head, as shown and described.
